W. J. WALSH

BOOKREST

Filed Oct. 13, 1921

FIG. 2

FIG. 4

Inventor:
William J. Walsh
By *Seth Weston Haughwole*
Atty.

Patented May 8, 1923.

1,454,197

UNITED STATES PATENT OFFICE.

WILLIAM JAMES WALSH, OF HAMILTON, ONTARIO, CANADA.

BOOKREST.

Application filed October 13, 1921. Serial No. 507,461.

To all whom it may concern:

Be it known that I, WILLIAM JAMES WALSH, a subject of the King of Great Britain, and a resident of the city of Hamilton, in the county of Wentworth, Province of Ontario, Dominion of Canada, have invented certain new and useful Improvements in Bookrests, of which the following is a specification.

10 My invention relates to improvements in book rests with particular reference to the general type described in my previous United States Patent No. 1,017,121 dated February 13th, 1912 and the object of the present invention is to provide a device of this character which will support the book normally in the closed position thus making the device more compact and permitting its installation in confined positions where it is either undesirable or impossible to install the open type rest, and a still further object is to permit a more free opening of the book whereby the inner portions of the pages adjacent to the binding are more freely exposed.

15

20

25

My present invention consists essentially of a spring controlled book rest hingedly supported in a bracket secured in an upright position upon a wall or other suitable place, a transversely curved back clamp hingedly mounted along one side edge of the book rest, inwardly bent flanges at each end of the hinged back clamp, retaining rods having their ends secured in the said flanges and extending longitudinally of the back clamp, and a stop limiting the swing of the hinged back clamp, all as hereinafter more particularly described and illustrated in the accompanying drawings in which;

40 Fig. 1 is a central vertical longitudinal section through my invention showing the rest in the lowered position and the book closed, the raised position being indicated in broken lines.

45 Fig. 2 is a plan view partly in section of a wall bracket used in the invention and a supporting arm for the book rest which is hingedly mounted within the wall bracket.

50 Fig. 3 is a perspective view showing the book rest, supporting arm therefor and a hinged back clamp carried by the rest.

Fig. 4 is an end view of the book rest with the book supported therein in the closed position.

Fig. 5 is a central cross section through the device showing the book in the open position for reading.

Like characters of reference indicate corresponding parts in the different views.

1 is a bracket rigidly secured to the wall 60 and is provided with the jaws 3 extending outwardly therefrom.

4 is a supporting arm carrying a transverse casing 5 at one end, which casing is hingedly mounted between the jaws 3 by means of the 65 bolt 6.

7 are end nuts for securing the bolt 6 in position.

8 is a coil spring which is carried by the bolt 6 and lies within a transverse opening 70 in the casing 5. One end of the spring 8 engages the under side of the bracket 1 at "A" while the other end engages at "B" the top face of a lip 10 formed at the extremity of the casing 5.

75 The supporting arm 4 is of semicircular cross section and 11 is a resilient spring sleeve formed to surround the arms 4 and to have flanges 12 and 13 extending on each side thereof.

80 The above described portion of the present invention is identical with that shown in my previous patent above referred to and will not therefore be described in further detail.

85 14 is the book rest proper which is made substantially of a size equal to or just slightly larger than the closed size of the hook 15 with which it is to be used.

90 The spring sleeve 11 is secured centrally to the under side of the rest 14 (see Fig. 3) and is mounted upon the supporting arm 4 by passing the sleeve over said arm, the stops 16 being then secured to the end of the arm 4 to prevent removal of the spring sleeve and rest therefrom.

95 The sleeve 11 fits snugly to and is adapted to tilt in either direction on the arm 4.

17 is a back clamp which is curved at 18 for a purpose as will presently appear.

100 The inner edges of the back clamp 17 and of the rest 14 carry hinge portions 19 and 20 respectively and the clamp 17 is hingedly

connected to the edge of the rest 14 by a through rod 21 which engages the hinge portions 19 and 20.

22 is a stop carried by the back of the hinged clamp 17 and is adapted to engage the under face of the rest 14 for limiting the degree of swing of the back clamp when the book is being opened (see Figs. 3, 4 and 5).

10 23 are flanges carried by each end of the back clamp 17 and 24 are retaining rods extending between the flanges 23 and secured by nuts 25. These rods 24 are disposed concentrically with the curved portion 18 of the

15 back clamp 17.

26 is the back edge or binding of the book 15 and is curved (see Figs. 4 and 5).

The construction and operation of my device is as follows:

20 The rest 14 is supported upon the arm 4 in exactly the same manner as described in my former patent above mentioned except that in the present case the rest is the size of the closed book only instead of that of 25 the open book and the arm 4 is situated centrally of the rest 14.

The device is primarily intended for use with books such as telephone directories and such like which are now made with a concave 30 curved back binding as shown at 26 (see Figs. 4 and 5) and in order to permit a full free opening of the book I make the back clamp 17 curved as at 18 and arrange the retaining rods 24 concentrically therewith and 35 also substantially concentric with the curved back of the book.

The book is secured in place by passing the rods 24 between the leaves thereof at the proper places and securing said rods by the 40 nuts 25.

The book mounted upon the device is shown in the closed position in Fig. 4 and in the open position in Fig. 5.

It will be seen from Fig. 5 that the construction permits an exceptionally free opening of the book so that the portion of the 45 pages adjacent to the binding are fully exposed.

This overcomes a difficulty in former 50 clamping devices for thick books since hitherto the clamping device which grasped the back portion of the book tended to pre-

vent such free full opening, thus rendering the reading of the inner portions of the sheets either impossible or at least extremely 55 difficult.

The spring sleeve 11 permits the tilting of the rest 14 to either side, as in my former patent, and will normally maintain the rest 60 level except when held so tilted by hand.

The spring 8 will of course normally tend to raise the book and rest into the closed positions indicated in broken lines in Fig. 1 but as this operation is identical with my former patent it will not be described here.

The stop 22 will limit the opening of the book so that it cannot open beyond the desired horizontal position for reading shown in Figs. 3 and 5.

While I have described the use of my invention primarily for use with books having curved backs it is, of course, applicable to books having the normal straight back in which case it will also permit an exceptionally free opening of the book.

Various modifications may be made in the details of construction without departing from the spirit of the invention or the scope of the claim and therefore the exact form shown is to be taken as illustrative only 75 and not in a limiting sense.

For instance I may dispense with the spring sleeve 11 and mount the book rest 14 rigidly upon the supporting arm 4.

From the foregoing it will be evident that 80 I have devised an improved book rest which will be of great value for use with telephone directories and other similar books of reference.

What I claim as my invention is:

In a device of the class described, the combination with a flat book rest, of a relatively narrow plate hingedly connected to one marginal edge thereof, book securing means carried by said hinged plate, a projecting rigid stop arm rigidly carried by the hinged plate, said stop arm adapted to engage the back of the book rest and limit the oscillation of the hinged plate.

WILLIAM JAMES WALSH.
